SAFETY LOCK FOR LICENSE PLATES

William T. Martin, Tampa, Fla.

Application January 17, 1947, Serial No. 722,636

5 Claims. (Cl. 40—125)

1

My invention relates to the attachment of display or license plates to holders customarily provided therefor at the front and rear ends of an automobile. These plates are frequently secured to the holders by ordinary cap screws or bolts, and are often stolen by thieves who unscrew the fastenings. Many devices have been developed to combat this thievery, but the construction of most of them is so complicated that the expense of producing them is greater than the saving made by their use.

My invention permits of a simple and inexpensive method of manufacture, coupled with an easy and practical method of attachment, and renders it impossible to remove the plate without destroying or substantially damaging it.

Other advantages of the invention are that the protective embossment hereinafter described may be stamped out in the same operation in which the plate itself is stamped, and the bolt and nut are of simple and easily manufactured design.

Other objects will be in part obvious from the annexed drawing and in part hereinafter indicated in connection therewith by the following analysis of this invention.

This invention accordingly consists in the features of construction, combination of parts, and in the unique relation of the members and in the relative proportioning and disposition thereof, all as more completely outlined herein.

To enable others skilled in the art fully to comprehend the underlying features of this invention, that they may embody the same by the modifications in structure and relation contemplated by the invention, a drawing depicting the preferred embodiment of the invention forms a part of this disclosure, and in such drawing like characters of reference denote corresponding parts throughout the several views.

In the drawings;

Fig. 1 is a front view showing my new license or display plate.

Fig. 2 is a cross-section taken along the line 2—2 of Fig. 1.

Fig. 3 is a top view showing the plate attached to an ordinary holder.

Fig. 4 is a front view showing the plate attached to an ordinary holder.

Fig. 5 is a cross-sectional view of the assembled device, taken along the line 5—5 of Fig. 4.

Fig. 6 is a side view of the bolt used in attaching the plate to the holder.

Fig. 7 is a side view of the nut into which the bolt is screwed.

2

Fig. 8 is a view of the inner face of the nut.

Fig. 9 is a front view showing my device when applied to a clip for locking on a present style license plate.

Fig. 10 is a cross-sectional view taken along the line 10—10 of Fig. 9.

Fig. 11 shows my device as applied to an annual tab used in those States which do not issue complete new license tags every year.

In the construction illustrated, a license plate 12 having apertures 13 for fastenings of the usual form, is provided with raised protective embossments 14 surrounding the apertures, the area contained within said embossments being slightly greater than the area of the respective apertures, thus forming a ledge to support the bolt head 23, said embossments being in turn surrounded by perforations 15. In Fig. 4 is shown a conventional license plate holder 16 having slots 17 for the securing means. The license plate 12 is so positioned adjacent the holder 16 that at least one of the apertures 13 in the plate 12 registers with one of the slots 17 in the holder 16. A nut 19, has a threaded recess 20, and a protuberance 21, the height of which from the surface of the nut is substantially the same as the thickness of the license plate holder 16. The width of this protuberance 21 is slightly less than the width of the slots 17 and its length is substantially greater than the width of said slots so that it fits loosely therein and holds the nut against rotation in assembled position.

The protuberance 21 of the nut 19, having been positioned within the slots 17 in the holder 16, so that the threaded recess 20 is aligned with the aperture 13 in the license plate 12, and the aperture 17 in the holder 16. A threaded bolt 22, having a head 23 with a screw driver slot so designed that the bolt may be turned in one direction only, is inserted in the aperture 13 of the plate 12, passed through the slot 17 in the holder 16 and screwed into the threaded recess 20 of the nut 19.

This having been done, the bolt cannot be unscrewed by a rotated blade, due to the beveled construction of the slot in its head. The nut cannot be turned, due to the fact that the protuberance thereof is held by the slot in the holder, and the bolt cannot be turned by pliers or similar tools, since access to the sides of the head is prevented by the protective embossment. In order to remove the plate, substantial pressure must be applied near the weakened portions 15 of the plate thus tearing the plate loose by breaking it at the weakened points. The bolt

may then be removed by gripping the embossment with pliers or other grasping means so tightly that the inside thereof is pressed against the head of the bolt, and then unscrewing the bolt by turning it together with the portion of the embossed plate remaining in place. The side of the bolt-head may be roughened, as shown in Fig. 6, in order to facilitate its removal in this manner.

The same method may be used for the attachment of an annual tab 24 as shown in Fig. 11, in which 25 represents a slot in the plate 26, and 27 is a projection of the annual tab 24 fitting into the slot 25 the width of which projection 27 may be less than that of the annual tab. The tab is then fastened on in exactly the same manner as the full-size license plate hereinbefore described, by a bolt of the type shown in Fig. 6 passing through an aperture 13' in the tab and an aperture in the license plate and screwing into a nut of the type illustrated in Figs. 7 and 8. Application of pliers or similar tools to the head of the bolt is prevented by an embossment 14' surrounding the aperture 13' in the tab. Said embossment is in turn surrounded by a weakened portion 15' of the tab 24, in order that it may be removed at the end of the year, in the manner hereinbefore described in connection with the full-size plate.

A form of my invention may also be used, as shown in Figs. 9 and 10, to lock on a license plate of the present type which possesses no protective embossment for the bolt-head. This is accomplished by the use of a metal clip 28, comprising two arms 29 and 30. The arm 29 is designed to fit over the front of the plate and has an aperture 13", and surrounding protective embossment 14" in turn surrounded by weakened portion 15" of the fork 29, just as hereinbefore described in connection with other forms of my invention. Said aperture 13" is so placed as to register with the usual aperture 33 in a license plate 31 when the bracket is fitted thereon. Fork 30 possesses an aperture 32 in like position, and after the bracket has been put in place the shank of the bolt 22 is passed in turn through the aperture 13", 33 and 32, and then screwed into a nut of the type illustrated in Figs. 7 and 8, all as shown in cross section in Fig. 10. Since this nut cannot be turned, and the bolt cannot be unscrewed by means of a rotated blade, or gripped by pliers or the like, for reasons hereinbefore set forth, the plate cannot be removed without tearing the material of which the locking bracket is composed, a difficulty which is likely to dissuade a prospective thief from attempting to remove the plate.

I claim:

1. In combination, a plate adapted for attachment to a holder having a slot therein, said plate having an aperture therein and a raised circular protective embossment surrounding said aperture but spaced therefrom to form a small recess, a bolt having a head fitting into said recess and so designed that it may be turned in

only one direction by a rotated blade, the portion of the plate surrounding the embossment being weaker than the rest of the plate so that said embossment may be crushed into frictional engagement with said bolt head thereby permitting removal of said bolt by the application of rotary force to the sides of said bolt head through said crushed embossment, and a nut having a protuberance with at least two parallel sides, said protuberance fitting into the slot in said holder with said parallel sides aligned with the sides of the slot, the length of said parallel sides of the protuberance being substantially greater than the width of the slot.

5 2. A combination as claimed in claim 1 in which the sides of the bolt head are roughened to facilitate engagement with said crushed embossment.

10 3. In combination, a plate and locking device 20 as claimed in claim 1, said plate constituting an annual tab for an automobile license tag, and an automobile license tag having at least two slots, one of said slots being adapted to pass said bolt and the other to receive one end of said annual tab.

25 4. In combination, a plate and locking device 30 as claimed in claim 1, said plate constituting an annual tab for an automobile license and carrying a tongue protruding from one edge thereof, and a license tag having at least two slots, one of said slots being adapted to pass 35 said bolt and the other having a length slightly greater than the width of said tongue and positioned on the license plate at a distance from the center of said first slot approximately equal to the distance from the aperture in said annual tab to the edge of said tab supporting said tongue, and extending in a direction parallel to said edge, so as to receive said tongue when the aperture in said tab is so placed as to register 40 against said first mentioned slot in said tag.

5 5. In combination a plate and locking device 45 as claimed in claim 1, said plate constituting an annual tab for a license plate and having two parallel arms adapted to fit over one edge of 50 said license plate, one of said arms carrying the aperture and surrounding embossment described in claim 1 and the other carrying a registering aperture.

55 WILLIAM T. MARTIN.
